CABLE TERMINAL

Fritz Gutmann, Schoneiche, near Berlin, and
 Erich Schulte - Herringen, Berlin, Germany;
 vested in the Alien Property Custodian

Application September 25, 1940, Serial No. 358,320
 In Germany October 18, 1939

6 Claims. (CL. 174—73)

This invention relates to the construction of the terminals of cables, especially high frequency cables. More particularly, the invention is concerned with cable terminals of the kind having a ceramic tube arranged to distribute the electric stress uniformly and to obviate puncturing or flashing-over. If nevertheless flashing-over occurs then the ceramic tube, acting as a glide path therefor, prevents danger of fire.

The invention consists in certain features of novelty that will appear from the following description and be particularly pointed out in the appended claims, reference being had to the accompanying drawing, which shows a longitudinal section of one embodiment of the invention.

The cable terminal illustrated by way of example has a tubular outer conductor 4 and a stranded inner conductor 7, embedded in an elastic insulation 2 which consists of a highly polymeric hydro-carbon compound of low dielectric losses. Over the end of insulation 2 a ceramic tube 1 is inserted which closely fits upon the insulation 2 with a view to avoiding any air cavity between the two. In order to provide for readily inserting the tube 1 over the insulation 2, the insulation is cleaned off with benzine. A band 3, made of the same material as the insulation 2, is wound around it to form a conical coil whose peripheral surface extends from tube 1 to the insulation 2. This coil aids in supporting the outer conductor 4 which is inserted over that end of tube 1 against which the coiled band 3 bears, and is pressed against the parts 1, 3 by a clamp 5. Band 3 is coiled around the insulation 2 so firmly as to avoid air cavities forming between the two. In this way, any air cavity between conductor 4 and insulation 2 will be precluded. Tube 1 has a torus 9 and is provided with a metal coating 11 between this torus and the coiled band 3.

The free end of the cable carries a clamp 6. The strands of conductor 7 are each fitted with a cable eye 8 and are fixed to the clamp 6 by means of the eyes 8 and of screws 10. They are thus arranged in rosette fashion. This arrangement acts to conduct the arriving heat effectually away and owing to the several cable eyes 8 also acts to decrease the detrimental influence of the skin effect of the soldered joints compared with a single soldered joint. It is attributable to this arrangement alone that the thermal stress at the junction points of the cable is not higher than it is within the cable. Experiments have shown that in the case of a single cable eye into which the entire inner conductor is soldered the

mere working current of the cable can destroy the strands within the cable eye.

Owing to the torus 9 the spark-over voltage between the clamps 5, 6 is several times, say 5 or 6 times, greater than otherwise.

What is claimed is:

1. A coaxial cable termination comprising an inner cable conductor, an insulating body of solid, elastic, insulating material encircling said inner conductor, a ceramic tube encircling said insulating body, said tube having an outwardly projecting torus on the external surface thereof adjacent one end thereof and the inner diameter of said tube being slightly less than the external diameter of said body in free space whereby said body is compressed by said tube and substantially all cavities between said tube and said body are eliminated, an outer cable conductor, at least a portion of said outer conductor encircling a portion of said tube at said one end thereof, and junction termination means for said inner conductor mounted on the other end of said tube.
2. A coaxial cable termination according to claim 1 wherein said solid, elastic, insulating material is a highly polymeric hydrocarbon compound.
3. A coaxial cable termination according to claim 1 further comprising a conductive coating on the exterior surface of said tube between said torus and the end of said tube encircled by said outer conductor.
4. A coaxial cable termination comprising an inner cable conductor having a plurality of strands, an insulating body encircling said inner conductor, a ceramic tube encircling and in contact with said insulating body, said tube being provided with an extending torus portion near one end thereof an outer conductor, at least a portion of said outer conductor encircling said tube at said one end thereof, and junction means mounted at the other end of said tube, said junction means comprising separate spaced terminals conductively interconnected for at least a plurality of said strands.
5. A coaxial cable termination according to claim 4 wherein said means comprises a clamp of conductive material and said terminals comprise screws threaded to said clamp and further comprising cable eyes fitted to said strands and fastened by said screws.
6. A coaxial cable termination comprising an inner cable conductor, an insulating body of solid, elastic, insulating material encircling said inner conductor, a ceramic tube encircling said insulating body, said tube having an outwardly

projecting torus on the external surface thereof adjacent one end thereof and the inner diameter of said tube being slightly less than the external diameter of said body in free space whereby said body is compressed by said tube and substantially all cavities between said tube and said body are eliminated, an outer conductor having a normal portion and a flared portion, the inner diameter of said normal portion being substantially equal to the external diameter of said body and less 10

than the external diameter of said tube and said flared portion being mounted to encircle a portion of said tube at one end thereof forming a space between said flared portion and said insulating body, and a band of insulating material encircling said insulating body and mounted in said space between said flared portion and said body.
